Application July 7, 1949, Serial No. 3,760

Term of patent 14 years

(Cl. D90—16)

To all whom it may concern:

Be it known that I, Clarence J. Ruppert, a citizen of the United States, residing at Washington, in the District of Columbia, have invented a new, original, and ornamental Design for Cycle Saddle Covers, of which the following is a specification, reference being had to the accompanying drawing, forming a part thereof.

In the drawing,

Figure 1 is a side elevation of the cycle saddle cover, showing my new design; and

Figure 2 is a top plan view of the same.

I claim:

The ornamental design for a cycle saddle cover, as shown.

CLARENCE J. RUPPERT.
